HARRY HUMPHREYS, OF BALLAMONA, DAVENPORT, ENGLAND, ASSIGNOR TO UNION BAG & PAPER CORPORATION, OF NEW YORK, N. Y., A CORPORATION OF NEW JERSEY.

FEEDING DEVICE FOR WEBS OF PAPER AND OTHER MATERIAL.

Application filed December 4, 1923. Serial No. 678,533.

To all whom it may concern:

Be it known that I, HARRY HUMPHREYS, a subject of the King of Great Britain and Ireland, and residing at Ballamona, Davenport, in the county of Chester, England, have invented certain new and useful Improvements in and Relating to Feeding Devices for Webs of Paper and Other Material, of which the following is a specification.

10 This invention relates to a method of and means or devices for correcting, regulating or adjusting the register or position of a mark or imprint upon a previously marked or printed web of paper, cloth, cardboard, 15 pulpboard or other material (hereinafter referred to as "material") relative to a device operative upon such at intervals in the length thereof, of the type wherein the material is automatically maintained in register by aid of perforations formed in the web in co-operation with a detecting device.

The invention has for its object the provision of an improved automatic method and means whereby the register of the mark or imprint upon the material is maintained or controlled with respect to the functions of the device operative upon the material at intervals in the length thereof.

According to the invention the relative 30 rate of feed of the material with respect to the functions of the device operative thereon at intervals in its length, is relatively retarded or increased by means actuated by or dependent for their actuation upon the position of the perforations in the material with respect to a point or detective device fixed as regards positions or constant in point of time and with respect to a controlling device timed to function in synchronization with the movements of the device operative upon the material.

The detector device may be in the form of electric means such as a feeler or electric contact adapted in certain circumstances to 45 establish a circuit through a perforation or orifice in the material, or such device may be pneumatic, operating either by compressed air or upon a vacuum system dependent upon the situation of an orifice or perforation relative thereto.

The controlling device may be in the form of a rotary switch or distributor in the case of an electrically operated method and

where pneumatic means are employed a valve, preferably of rotary form, may be utilized. Further, the controlling device may be embodied or incorporated in the detecting device by causing the latter to be moved or rotated in synchronism with the movements of the operative device.

The invention also comprises a method of regulating or controlling the position of a mark or imprint upon a previously marked or printed web of material relative to a device operative upon such material at intervals in the length thereof, consisting in continuously drawing or tending to draw or feed a longer or shorter length of material than is required according to the intervals at which it is designed or intended the material is to be operated upon in relation to the mark or imprint and in automatically retarding or advancing the rate of feed of the material in accordance with the excess of deficiency of material tending to be delivered to the operative device.

The invention further consists in making an electric contact through an orifice in the material to cause electric current to flow, introducing the use of a secondary or modified circuit, and controlling the duration of the secondary in timed relationship with the function of the operative device so as to effect any desired alteration in the relative position of the mark or imprint to the operative device.

The invention also comprises making an electric contact through an orifice in the material to cause electric current to flow, and controlling the duration of flow in timed relationship with the function of the operative device so as to effect any desired alteration in the relative position of the mark or imprint to the operative device.

It is pointed out that alterations in the rate of feed of material or lengths of material operated upon are relative and that the invention includes: change of rate of feed or length of material delivered to an operative device operating at a constant speed, and a constant rate of feed or length of material delivered to an operative device actuated in a variable manner either as regards time or position, that is to say, the intervals of time at which the operative device functions may be varied (increased or

decreased) or the longitudinal position at which such device operates with respect to the means delivering the material may be adjusted towards or away from such delivery means. Thus in reading the foregoing and following description, consequent modifications must be included with the terms employed.

The operative device above referred to 10 may be a device or mechanism adapted to impose a further mark or imprint upon the material, either by superimposition or in spaced relationship to the first mark or imprint, or the device may be one adapted 15 to sever, fold or perforate the material in relation to a mark or imprint.

The term "perforation" is intended to include any slot or aperture in the material or any formation or increase in thickness 20 by the aid of which electrical contacts may be made or energy released.

Perforations in the material should be disposed in predetermined relation to the imprint and with respect to the controlling 25 device whether such device be operated in unison with the severing or other device or otherwise.

In the accompanying drawings:—

Figures 1 to 5 diagrammatically represent 30 various modes of carrying the invention into effect.

Fig. 6 is a diagrammatic view of a machine illustrative of my invention; Fig. 7 is a diagrammatic view of a detail.

In carrying the invention into effect according to one convenient mode, as applied by way of example to a machine which is adapted to be supplied with a previously printed web of material bearing a series of perforations or apertures, each of which is situated in a definite or substantially constant relationship with an imprint, an appropriate roller in the machine, preferably a roller such as A (Figure 1) over which the material is introduced into the machine, is provided with a continuous metal contact device. This may be in the form of a metal band encircling a portion of the roller or the roller itself may be entirely of metal so that it may act as a conductor for electric current. The material 10 indicated by the dot-dash line is adapted to pass over this roller A in its travel into the machine and in alignment with the path of the series of perforations or apertures a detector or fixed contact brush α (hereinafter termed "the detector brush") is mounted, so that as each orifice passes beneath the brush contact is established between the brush and the roller or band and current may flow from the brush to the roller (or band) or vice versa.

In order to convey current to or from the roller a second brush or contact α' (hereinafter called "the feeder brush") is mounted 65 in an appropriate position so that it will

continuously bear upon the metal roller or upon the metal band in the case where the whole of the roller is not conductive.

In any suitable situation upon or adjacent the machine, a rotary controller or distributor B is provided which may be in the form of a metal disc mounted upon trunnions or upon a shaft so that it may be rotated. The edge of the disc is provided with a strip or short sector of insulating material b so that any contact device bearing upon the edge of the disc will ride over the insulating strip once during each revolution.

According to the preferred form two contact brushes b' and b^2 are provided which are adapted to ride upon the edge or periphery of the controller or distributor disc and are connected by electric leads in a circuit to be hereinafter described.

A third contact brush b^3 is provided 85 which engages the disc so that it may act as a feed or return path for current to or from the controller disc.

Feed rollers 11—12 of the usual type adapted to draw and deliver the web to a severing device 13 are provided but are so driven or set that they continuously advance or tend to feed to the severing device a greater length of material than is required for the purpose for which the material is severed into lengths. One of these draw rolls (or both of them) is provided with a brake 14 adapted to be actuated by a solenoid or other electrical or electro-mechanical device 15; with a view to retarding the operations of the draw rolls to cause such (instead of delivering an excess of material) to deliver that length required according to the correct size of length to be severed. The retarding of the draw rolls 105 may be accomplished by providing a frictional drive therefor and permitting slip to take place.

According to another form the draw rolls may be positively driven so as to tend to deliver an excess to the severing device and a device may be provided which is adapted to act in the nature of a brake 16 (Fig. 7) upon the material or a variable extension of its path, before the material reaches the draw rolls. When such device is operated the material will be momentarily held back from the draw rolls causing same to slip and consequently deliver a decreased length of material to the severing device than they would deliver in operating upon the material when unretarded.

The brake or functionally equivalent mechanism, whether upon the draw rolls themselves or adapted to act upon the material previous to its entry between the draw rolls, may be provided with means whereby the retarding or braking effect may be varied or adjusted by manipulation.

The rotary controller or distributing disc 130

B is driven and rotated in synchronism with the severing device 13, that is to say, in the present instance for each operation of the severing device upon the web the rotary control disc B makes one revolution.

Contact brush b' bearing upon the edge of the rotary disc is connected to one pole (say the positive) of a suitable source of E. M. F. by the lead 1. Brush b² is connected by the 10 lead 2 to the feeder brush a'. The detector brush a is connected to the other pole (negative) of the source of E. M. F. by a line 3 which includes in its electric circuit a relay device 4 which when actuated is adapted to 15 draw down an armature or switch member 5, so that the switch member or armature is connected in the circuit to the negative pole of the source of supply.

The third brush or contact b³ is connected 20 (line 6) to the armature or switch arm 5 of the relay 4. Across the relay device or in any other suitable situation a parallel circuit 7, 8 is provided adapted to convey current to the solenoid or other electric or electro-mechanical brake operating device 15 at the draw roll end of the machine.

The contacts b' and b² of the distributor or controller B are spaced apart at an appropriate circumferential distance, so that 30 in view of the direction of rotation of the disc (indicated by the arrow) they are separated in point of time by any period up to that approximately corresponding to a length of material delivered to the severing 35 device for the full length required.

The situation of the brush b' may be adjusted by any suitable means towards or away from the contact b² according to the period for which it is desired the brake 40 should operate.

In operation the rotary controller device B is set so that at the moment the severing device 13 severs the web, the insulation strip is under the contact b² of the rotary controller.

Assuming the paper web is being delivered or fed to the severing device with its imprint in correct register with the operation of the latter and the correct lengths of 50 web are being delivered, the detector brush a will make contact with its roller A through a perforation in the material simultaneously with the arrival of the insulation strip b beneath the brush b² and consequently no current will flow in the electric circuit. Should, however, the feed rollers deliver a longer length of material to the severing device than is requisite, the corresponding perforation in the web will arrive at the detector brush a prior to the arrival of insulation strip b beneath the contact b². In such circumstances the electric circuit will be completed through the perforation in the web in what may be the primary circuit, viz, (see 60 Figure 1) positive lead 1, brush b', conduct-

ing body of controller disc B, brush b², feeder brush a', roller or band A, detector brush a, relay 4 and negative lead 3, causing the relay device to operate the switch or armature 5 and place the brush b³ in electric 70 circuit. Almost immediately the continued rotation of the controller B causes the primary circuit to be broken at a point away from the material by reason of the insulating strip b coming under the brush b², or by 75 reason of the material intervening at the detector brush, in which circumstances the current will flow or be maintained in what may be referred to as the secondary circuit, viz, from brush b' direct to the brush b³ (through 80 the disc B) and through the armature or switch 5, lines 7 and back to the negative pole through the lines 8 and 3. Thus the maintained secondary circuit comprises positive supply, brush b', controller disc, 85 brush b³, armature or switch 5, relay coils 4 and negative lead 3 with the brake circuit 7 and 8 in parallel. The establishment of this circuit causes the brake or equivalent device 14-15 to operate at the draw rolls and 90 retards the feed of material correcting the defect which has given rise to the establishment of the circuit. The secondary circuit will be maintained until the insulating strip arrives at the brush b' when the circuit will 95 be broken, only to be re-established again when a perforation arrives underneath the detector brush before the insulating strip b coincides with or meets the brush b².

According to a modification, instead of 100 providing a fixed detector brush, a rotary detector brush or contact maker may be employed. In this form the upper roller A (Figure 2) of the rear draw rolls (or other appropriate roller) is provided with an arcuate brush or contact maker a located in the path of the perforations upon the material. The rotary contact brush under certain conditions is adapted to make contact with a 105 lower roller A' through the perforations or 110 apertures in the material.

The rollers A, A' should be driven synchronously with the severing device.

The lower roller A' may be made entirely 115 of conducting metal, or a portion thereof, such as a band, may be adapted to act as a conductor.

The roller A' or its band has a constant electrical connection by the aid of a brush b². A second brush b³ is provided for the roller or band situated in the path of an insulation strip or block b with which the roller or band is provided. In this modification the primary circuit comprises the positive source of supply, leads 1 including relay coils 4, rotary detector brush a, body of the roller A' or its band, contact brush b² and return lead 3 to negative supply. The secondary circuit comprises positive source of supply, relay coils 4 and parallel circuit 7, 8 of brake de- 120 125 130

vice, armature or switch arm 5, contact b^3 , body of roller A' or its band, brush b^2 and return to negative supply.

It is to be noted that in the present and in the hereinbefore described manner of carrying the invention into effect the parallel circuit 7, 8 is included in both the primary and secondary circuit but is referred to as being part of the secondary circuit as it continues to carry current after the primary circuit is broken.

In operation the rotary detector brush a is set so that the perforations in sequence pass in rear of, and preferably just in rear or behind of it, and this relative situation of the detector brush and the perforations are synchronous with the operations of the severing device whenever the correct length of web is delivered to the severing device.

Assuming the material to be correctly in register it will be appreciated that a perforation arrives between the two rollers A, A' too late to be engaged by the rotary detector brush a so that the latter cannot establish electric circuit with the roller beneath it, but as soon as the draw rolls feeding the severing device advance a greater length of material than required, the next aperture or perforation will arrive at the point of contact between the two rollers A, A' before the rotary detector brush a has left the peripheral point of contact and, consequently, electric contact will be established through the aperture and the primary circuit will be established via the brush b^2 .

The making of the primary circuit immediately causes the armature or switch arm 5 to introduce the secondary circuit via the contact b^3 . As soon as the perforation and rotary detector brush a pass away from the contact roller or band A', the primary circuit is broken. The secondary circuit will be maintained during the rotation of the insulation strip b until it reaches the contact b^3 when the secondary circuit will be broken.

The duration of the current in the secondary circuit depends upon the situation of the brush b^3 and the position of the insulation strip in its rotary path with respect to the time at which the perforation arrives under the rotary detector brush a . For the purpose of varying the period over which the brake is applied to the draw rolls by the maintenance of the secondary circuit the situation of the brush b^3 may be adjusted by any convenient means in an arcuate path.

In carrying the invention into effect according to another mode (see Figure 3) a roller A² of the machine is driven or rotated at a speed in unison with the severing or operative device and is provided with supplementary rolls d or other means whereby the material indicated by dot-dash line is caused to travel in contact with the roller A² over a substantial portion of its circumference. In

the region where the material travels in contact with the roller an arcuate contact plate or conductor C is located either lightly touching the material or just spaced therefrom.

Upon or in the roller A² is mounted a spring-pressed plunger a , located in the path of the perforations in the material and connected by lead 2 in an electric circuit, the making of which either directly (or indirectly by aid of a secondary circuit) actuates means for altering the position of the imprint or mark upon the material relative to the severing or operative device. The arcuate contact plate C is also electrically connected in the circuit preferably to the positive source of supply.

The branch leads 7, 8 extend to the brake device or other means for altering the position of the imprint with respect to the severing device, so that such device or means is included in the circuit as indicated in the figure.

When the spring-pressed plunger a registers with a perforation, contact is established between the plunger and the arcuate plate C. During the rotation of the plunger in contact with the material the arcuate plate supports the plunger and obviates any effect the latter might otherwise have to puncture or bulge the material at the point of contact.

In operation the roller A² is set so that when the material is in correct register with the severing device the perforations on the web pass in rear of the plunger a so that no electric circuit is established. When the material is out of register a perforation will coincide with the plunger a and travel with it over the interval during which the material travels through the zone of the arcuate plate C. Consequently, the plunger a will contact with the arcuate plate C and establish the electric circuit which is to cause the actuation of the means for altering the disposition of the mark or imprint in relation to the function of the severing device and this contact will be maintained for the whole of the period during which the plunger travels over the arcuate plate.

The period during which the electric circuit is maintained may be varied by providing means whereby the effective length of the plate may be varied.

The foregoing description has been confined to the application of the invention to instances in which the draw rolls are driven or set to feed an excess of material. The invention may, however, be carried into effect by arranging for the draw rolls constantly to deliver a less quantity of material than is desired. In this circumstance, the controlling means brought into operation by means of the detector device are adapted to operate mechanism or cause

mechanism to be operated to accelerate or increase the feed of material to the severing or operative device as circumstances arise which necessitate a correction of the feed.

5 According to one simple mode of carrying out this application of the invention, the forward draw rolls 11' may have a brake device 16 (Fig. 7) initially set consistently to restrain them from delivering that 10 quantity of material which their circumference and/or rate of revolution according to their gearing would cause them to deliver were they unrestrained. Immediately 15 the machine begins to operate to deliver in sufficient lengths of material, the detector device establishes a circuit upon the lines of any of those previously described and causes the brake to be relieved, whereupon the rollers immediately commence to advance 20 the greater length of material which they would normally have fed had their operation been unrestrained. The roller will continue to advance the increased lengths of material until the deficiency is made up 25 when the brake is again applied.

According to a modification the detector device may be adapted to control both acceleration or increase in rate of feed and retardation of the material according to 30 whether it has lagged or crept with respect to the severing device. This may be accomplished by providing a reversible motor, for example, as shown in Avery Patent No. 1,517,099, November 25th, 1924, 35 adapted to operate a compensating or sun and planet drive for the draw rolls. Alternatively, a pair of brakes may be utilized, one 16 (Fig. 7) adapted to maintain a constant speed in the feed rollers until released 40 when an increase of speed would occur, and another brake 17, the effect of which may be superimposed on that of the first brake to cause retardation of the material.

In the case of control by acceleration and 45 retardation, a pair of detectors may be arranged so that when lag or creep occurs, one or other of duplicate circuits is made or introduced to operate the appropriate brake.

In carrying the invention into effect for 50 producing a retardation or an increase of rate of feed to the severing or operative device, according to whether the material has crept forward or lagged behind a predetermined or normal rate, an appropriate roller A of the machine is provided with a pair 55 of detector brushes or contacts a, a*. These brushes may be conveniently spaced apart at the periphery of the roller A a sufficient distance to permit a perforation to lie midway between the two and so that if a perforation be a fraction (or a predetermined period) early or late in arriving at one or other of the detector brushes, the appropriate circuit will be established by aid of 60 one of two controllers or distributors. A

third brush a' similar to the feeder brush already described is provided for the roller A and adapted to act as a constant electrical feeding contact device.

Two controllers or distributors B and B' 70 are provided which rotate in synchronism with the operations of the severing or other device. Each controller has three brushes, viz: e, e' and e² in association with the controller B which takes care of the retardation circuit, and f, f' and f² in association with the controller B' (acceleration). An insulation strip or block b, b' is provided for each of the controllers.

Relay devices 4 and 4^a provided with 80 armature switches 5 and 5^a are employed in the circuits for introducing parallel control circuits 7, 8 and 7^a, 8^a into the secondary circuits upon the principle already described.

The leads 7, 8 extend to a device 16-18 adapted to effect the acceleration or speeding up of the forward draw rolls and the leads 7^a, 8^a control the retardation of the draw rolls. The devices employed at or 90 in conjunction with the draw rolls for effecting these purposes may be of any appropriate kind; for example, a reversible motor or brake means may be adopted as hereinbefore indicated.

95 The various brushes, relay and switch devices are connected up as shown in Figure 4. The controllers B, B' are set so that under normal conditions when the feed is as desired and the material is in correct register 100 with the severing or operative device, the insulation part b is due to come under the brush e and the part b¹ is due to leave the brush f at the moment when a perforation passes beneath the brush a on the one hand and beneath the brush a* on the other.

For convenience and having regard to the short arcuate contact the material has with the roller A, the setting may be arranged so that a perforation lies midway between the brushes a and a* when the insulation strips are in the position indicated above and as diagrammatically represented in Figure 4 of the drawings.

In circumstances in which the material 115 has a longer contact with the roller or for any other reason the brushes a and a* may be spaced differently, the essential point to be observed being the time element as regards the position of the insulation strips in 120 reference to their brushes at the moment when the perforations pass beneath such. The position of the brushes e, e² and f, f² may be adjustable in order to vary the period during which the secondary circuit 125 is maintained and, consequently, the length of time during which the means adapted to cause the correction of the material are operative.

In operation, assuming the material to 130

- have worked out of register by creeping forward, a perforation will reach the brush a earlier than normally and, consequently, before the insulation strip b has arrived under the brush e . Thus a path is open to the current, via: brush e^2 , controller B, brushes e , a' , a and through the relay coils 4^a to the negative. The switch 5^a is closed by the energizing of the relay coils, introducing the secondary circuit which maintains the current in the parallel circuit 7^a , 8^a , to cause the retardation of the material, until broken by the insulation strip b as it meets the brush e^2 .
- Should the material have lagged, a perforation will arrive late at the brush a^* and at a time when the insulation strip b' has left the brush f , causing the primary circuit to be made and the secondary circuit introduced to cause the acceleration or speeding up of the material after the manner already described in connection with the retardation effect.

When the material is in correct register it will be observed that the circuit for the current is open through both controllers by reason of the engagement of the insulation strips with their respective brushes.

In carrying the invention into effect according to an alternative arrangement to that above described for effecting the control of the material in both directions, a single controller B (Figure 5) may be employed. The roller A, brushes a , a^* and a' and the relay coils, armature switches and parallel circuits, are arranged as already described in connection with the modification represented in Figure 4. According to this arrangement the brushes a and a^* should be situated only so far apart as to admit of a perforation conveniently to be accommodated between the points of contact.

The controller B is provided with three brushes, e' and e^2 , the brush e^2 being adjustable in order to control the period during which the acceleration or retardation of the material is effected.

The setting of the parts according to this modification of the invention should be such that the insulation strip b arrives in the situation shown in Figure 5 when the material is in correct register with the severing or operative device and the perforations arrive on time between the detector brushes. The dimension of the insulation strip b and its setting should be arranged so that a small margin of contact for the brushes e , e' with the conducting part of the controller and on each side of the insulation strip, is allowed in respect to the predetermined amount of lag or creep upon which the required corrective operation commences. This margin is sufficient to allow the primary circuit to be established to actuate the secondary circuit, when a perforation arrives

early or late, as the case may be, at the detector brush a or a^* , respectively, before the primary circuit is broken by the insulation strip passing beneath the brush e .

In operation when the material has crept forward, a perforation arrives at the brush a earlier than it should do but, nevertheless, before the insulation strip b has passed under the brush e by reason of the margin above referred to. Similarly when the material has lagged and a perforation arrives a fraction late at the brush a^* , a path is still open for the current from the brush e to the brush e' through the controller B. When the rate of feed is normal the rear of the insulation strip b lies under the brush e' when the perforations pass beneath the brush a^* and when the perforation advances under the brush a the insulation b is under the brush e , so that in either case the circuit for the current is open and no correction takes place.

It is preferred to rotate or operate the controlling device in unison with the severing or other device but in certain applications of the invention where high speeds are involved it may be found convenient to cause the controlling device to make only an appropriate fractional rotary movement for each operation of the severing or other device. In such cases the brush which functions with the controller for establishing the circuit in the first instance is caused to contact with a supplementary insulation over a portion of the circumference arranged so that the circuit cannot be established through this brush except when the controlling device occupies that position in respect to the brush in connection with which a particular series of perforations is timed to operate. In other words, for example, when the controlling device is set to make, say, half a revolution for each operation of the severing device the particular series would be alternate perforations and when the inappropriate alternate perforation arrived at the detecting device the brush would lie on the supplementary insulation. Alternatively, this end may be achieved by retaining the arrangement as, for example, shown in Figure 1 and in providing the material with perforations spaced at intervals corresponding with the time taken for the fractionally driven controller to make one complete revolution.

According to another manner of carrying the invention into effect, the perforations in the material may be utilized as vents for a pneumatic system operating either upon the compressed air principle or upon a vacuum system.

The registration of an orifice in the material may either directly or indirectly through a controller or valve operate an electric switch mechanism to introduce a cir-

cuit for controlling the material according to any of the means above described. Alternatively, the pneumatic means may function entirely upon a pneumatic system, the pressure or vacuum effect being conveyed to an appropriate mechanical device by conduits to operate means for advancing or retarding the material with respect to the severing device.

10 According to one mode of carrying the invention into effect upon the compressed air or vacuum system, pneumatic orifices or a slot form of orifice may be adapted to co-operate with the material which when the 15 material is in the correct situation, although registering with an orifice, will not cause the devices dependent thereon to function owing to the situation of a rotary controlling or master valve, such valve being set to 20 function synchronously with the severing device and permit the pneumatic pressure or vacuum to take effect only when a hole or perforation in the material arrives late or early with respect to the situation of 25 the valve.

Having now described my invention, what I claim as new and desire to secure by Letters Patent is:—

1. A method for the purposes and of the 30 kind described comprising retarding or increasing the relative rate of feed or delivery of the material according to whether a perforation in the material arrives early or late in respect to a predetermined normal moment of arrival at a stationary detector or detectors and in respect to the arrival at a certain point of a moving element removed from the material and timed 35 constantly to arrive at that point in synchronism with the operations of the severing or other device.

2. A method for the purposes and of the 45 kind described comprising continuously feeding or tending to feed a longer or shorter length of material to the severing or operative device than is required according to the intervals at which it is intended the material is to be operated upon in relation to the mark or imprint and automatically retarding in the one case or advancing in the other the relative rate of feed of the material to the severing or other device according to the disposition of a perforation in the material in respect to a fixed or predetermined point.

3. A method for the purposes and of the 60 kind described comprising continuously feeding or tending to feed a longer or shorter length of material to the severing or operative device than is required according to the intervals at which it is intended the material is to be operated upon in relation to the mark or imprint and automatically retarding in the one case or advancing in the other the relative rate of feed of the mate-

rial to the severing or other device according to the disposition of a perforation in the material in respect to a fixed point, and in reference to the arrival at a certain point of a moving element timed constantly to 70 arrive at that point in synchronism with the operations of the severing or other device.

4. A method for the purposes and of the kind described comprising feeding or delivering material to a severing or operative device at the normal rate required according to the intervals at which it is intended the material is to be operated upon in relation to the mark or imprint and either automatically retarding or advancing the relative rate 75 of feed or delivery of the material, dependent upon the early or late arrival of a perforation at one or other of a pair of stationary detecting contacts or devices and in respect to the arrival at a certain point of 80 a moving means timed constantly to arrive at that point in synchronism with the operations of the severing or other device.

5. A method for the purposes and of the kind described comprising establishing a 90 primary electric circuit through a perforation in the material, causing the current in such circuit to introduce a secondary circuit, causing the latter circuit to be maintained for a period and utilizing the current 95 to operate means adapted to retard or advance the relative rate of feed of the material to a severing or other device.

6. A method as claimed in claim 5, characterized in this, that the primary circuit 100 is made through a perforation in the material and broken at a point away from the material.

7. The method of feeding a web of material having a series of perforations therein 105 and acting thereon at predetermined intervals in the length thereof, which comprises feeding the web along, closing an electrical circuit through a perforation in the web when the web is out of register upon reaching the device for acting thereon at predetermined intervals, and utilizing the energy in the circuit for causing the feed of the web to be modified so as to thereafter cause it to come in proper register with the 110 device for acting thereon at intervals.

8. In a device of the character described, feed rolls, a device for acting upon a web of material having a plurality of perforations therein and fed by said feed rolls, controller means operating synchronously with said device for acting on said web, a detector device for closing an electrical circuit through a perforation in said web, means for permitting a circuit to be closed through 115 said detector device and controller when the web reaches the device for acting thereon out of proper register therewith, and means controlled by said circuit for modifying 120 the speed of movement of the web so as to 125 130

cause the same to reach the device for acting thereon in proper register.

9. In a device of the character described, feed rolls for a web of material having a plurality of perforations therein, a severing device for severing predetermined lengths of material fed thereto by said feed rolls, a detector device, a controller, means for permitting an electrical circuit to be closed through a perforation in the web and through said detector device and controller when the web reaches the severing device out of proper register therewith, and means controlled by said circuit for modifying the movement of the web to cause the same to reach said severing device in proper register.

10. In a device of the character described, feed rolls for a web of material having a plurality of perforations therein, severing means for severing predetermined lengths of said material fed by said feed rolls, a controller operating synchronously with said severing device, means for closing a circuit through a perforation in said web and through said controller when the web reaches the severing device out of proper register therewith, means controlled by said circuit for causing the feed of the web to be modified so as to cause the same to reach the severing device in proper register, and means to prevent the closing of said circuit when the web reaches the severing device in proper register therewith.

11. The method of feeding a web of mate-

rial having a series of perforations therein and acting thereon at predetermined intervals in the length thereof, which comprises feeding the web along, closing an electrical circuit through a perforation in the web when the web is out of register upon reaching the device for acting thereon at predetermined intervals, and utilizing the energy in the circuit for causing the relative action of the device for acting on the web and the travelling web to be modified to cause the same to come in proper register.

12. In a device of the character described, feed rolls for a web of material having a plurality of perforations therein, means for acting thereon at intervals in the length thereof, a controller operating synchronously with said severing device, means for closing an electric circuit through a perforation in said web and through said controller when the web reaches the means for acting thereon out of predetermined proper register therewith, means under the control of such circuit for causing said device for acting on said web at intervals and said web to come in proper predetermined register, said controller having insulating means for preventing the closing of said circuit when said web and said means for acting thereon at intervals come in proper predetermined register.

In testimony whereof I have signed my name to this specification.

HARRY HUMPHREYS.
